WHEEL

Donald J. Reid, Pleasant Ridge, Mich., assignor to Kelsey-Hayes Company, Romulus, Mich., a corporation of Delaware

Filed Nov. 5, 1969, Ser. No. 19,950

Term of patent 14 years

Int. Cl. D12—14
U.S. Cl. D14—30

FIG. 1 is a front elevational view of a wheel embodying my design;

FIG. 2 is a sectional view thereof taken along the line II—II of FIG. 1;

FIG. 3 is a fragmentary, sectional view taken generally along the line III—III of FIG. 1; and

FIG. 4 is a perspective view of the wheel of FIG. 1.

I claim:

The ornamental design of a wheel, substantially as shown.
